UNITED STATES PATENT OFFICE.

CHARLES W. BARTHOLMES, OF COALINGA, CALIFORNIA.

DEEP-WELL PUMP.

1,193,752.

Specification of Letters Patent. Patented Aug. 8, 1916.

Application filed June 30, 1914. Serial No. 848,197.

To all whom it may concern:

Be it known that I, CHARLES W. BARTHOLMES, a citizen of the United States, residing at Coalinga, in the county of Fresno 5 and State of California, have invented certain new and useful Improvements in Deep-Well Pumps, of which the following is a specification.

The object of my invention is to provide a sucker rod piston to be made integral with 10 the sucker rod, or as a coupling to be screwed into a sucker rod, which is connected to the plunger or piston of the usual type of pump attached on the lower end of a string of pipe 15 in the well.

The object of my invention is to assist in lifting the oil and sand in the regular process of pumping a well; to eliminate excessive buckling of the sucker rod in pumping due to the prescribed narrow limits 20 between the sucker rod piston cage, and the interior diameter of the pipe, thereby assuring maximum stroke of pump plunger; to insure concentricity of the sucker rods in 25 the event of buckled tubing by reason of the aforesaid prescribed narrow limits between the sucker rod piston cage and tubing; to eliminate contacting with ends of tubing between couplings while in operation or when 30 pulling the plunger or main piston for the purpose of renewal or cleaning the well by reason of absence of projecting parts in the correlative members of the device; to provide means for packing in order to obtain 35 closer refinements in relative sizes of the device and interior of pipe, as for example, between joints of threaded union and their corresponding nipples of the upper and lower cage, or by recessing the exterior periphery 40 of the union; and with these and other objects in view my invention consists of the parts and combination of parts as will be more fully hereinafter pointed out.

In the drawings:—Figure 1 is a vertical 45 sectional view of a pumping well showing the tubing, sucker rods, barrel, valves and anchor, parts being in elevation; Fig. 2 is an enlarged detail side elevation of my improved integral piston and sucker rod; Fig. 50 3 is a top plan view of Fig. 2; Fig. 4 is an enlarged detail side elevation showing the piston on a coupling adapted to be screwed to the sucker rod; Fig. 5 is a top plan view of the same.

55 In Fig. 1 I have shown the relative position of the usual deep well or plunger pis-

ton, (which I in the following will call "main piston") to the sucker rods when in the well and have incorporated the dash valves in the sucker rod pistons embodying 60 my invention, in the position they would occupy under working conditions, from which it will be seen that my improved dash valves and sucker rod pistons are not integral with the main piston, but are a part of 65 the sucker rod, and coact with the main piston in lifting the fluid.

The main piston occupies a position on the lower end of a string of tubing in the well.

The reference numeral 1 designates the 70 usual tubing which terminates at the lower end in a perforated pipe or anchor 2. The main piston 3 is mounted in the tubing or working barrel. The complete sucker rod 4 is made up according to my invention of a 75 series of rod and piston sections which will now be described in detail.

According to Fig. 2 the sucker rod pistons are formed integral with the sucker rod and consist of an upper cage 5 having lugs 6, 80 there being a space 7^a for the escape of fluid therebetween. At the bottom of the cage a valve seat 8 is formed in which the ball 7 is adapted to be seated to close the valve as the sucker rod is lifted thereby preventing the 85 return of fluid lifted over the cage on the downward movement of the rod. Depending below the cage is a screw threaded nipple 9, the nipple being tubular and its upper end forming the above described valve seat. The 90 lower cage 10 is made in accordance with the description of the cage 5 with the exception that there is no ball therein. These two sections of the sucker rod are securely coupled together by means of the screw threaded 95 union 11 which has a screw threaded engagement with the nipples of the upper and lower cage as shown, the union with the two nipples forming the actual sucker rod piston. There are a series of these cages or 100 sucker pistons extending throughout the length of the sucker rod as more clearly shown in Fig. 1.

As shown in Fig. 4 I may construct each sucker rod piston as a coupling, whereas 105 the construction is like that described in connection with Fig. 2, the only difference being that on the upper end of the coupling I form a screw threaded socket 12 into which one end of a section of a sucker rod 110 proper is screwed, while on the other end I form a male screw threaded member 13

which is adapted to be screwed into a screw threaded socket of another section of the sucker rod.

It is my intention to place these sucker 5 pistons with their dash valves at intervals on the sucker rod either integral with it or arranged on a coupling to be screwed into 10 couplings of the sucker rod as above described. The sucker rod pistons, in inductive order will be above the main piston at the lower end of the sucker rod and will extend to the height of the rods.

In operation the main piston is the im- 15 pellent in moving the fluid while the sucker rod pistons are in reality buckets, and the ball within the top cage is for the purpose of effecting a closure to prevent the early ac- 20 tion of the fluid on the upward stroke of the main and sucker pistons. The ball is raised on the downward stroke of the piston, thereby permitting the flow of liquid through the valve and thence through the openings in the upper cage.

I claim:—

- 25 1. A piston for deep well pumps comprising a pair of oppositely positioned cage members, a union for rigidly connecting said members, a ball in the cage, said union being tubular in order to form a seat for the ball and together with it constituting a dash valve.
- 30 2. In a deep well pumping apparatus, the

combination with a sucker rod made in sec- 35 tions, of a piston member including a valve formed on one section, a screw threaded nipple extending from said section, a piston member formed on the end of another section, a screw threaded nipple extending from said member, and a union having a screw threaded engagement with said nipples to couple the said piston members in 40 intimate working relation whereby said sucker rod carries a series of pistons on it throughout its length, said union forming a seat for said valve and permitting fluid 45 communication through the two adjoining pistons.

3. In a deep well pump having a main valve and a rod therefor; said rod comprising a plurality of pistons, each piston in- 50 cluding a pair of oppositely positioned cage shaped members, a tubular union rigidly connecting said members and a ball within the cage portion, the end of said union forming a seat for said ball and constituting 55 therewith a dash valve.

The foregoing specification signed at Coalinga, California, this ninth day of June, 1914.

CHARLES W. BARTHOLMES.

In presence of—

CHARLES R. COLE,
J. M. CLARKE.
